UNITED STATES PATENT OFFICE.

WILLIAM S. WICKHAM, OF WASHINGTON, DISTRICT OF COLUMBIA.

COLLAR-FASTENER.

1,202,940.

Specification of Letters Patent. Patented Oct. 31, 1916.

Application filed May 26, 1915. Serial No. 30,478.

To all whom it may concern:

Be it known that I, WILLIAM S. WICKHAM, a citizen of the United States of America, residing at Washington, District 5 of Columbia, have invented certain new and useful Improvements in Collar-Fasteners, of which the following is a specification.

This invention relates to collar fasteners, being more particularly directed to a 10 unitary device particularly adapted for securing in place of collars.

The main object of the invention is the production of a fastener constructed preferably of a single length of material, with 15 parts arranged for the convenient application of the fastener to the article to be secured, for interlocking the fastener with the article to prevent the accidental disconnection thereof, and further with parts arranged 20 for connection of the fastener with the neck band of a shirt.

The invention in the preferred embodiment of details will be described in the following specification, reference being had 25 particularly to the accompanying drawing in which:

Figure 1 is a perspective view of a collar, with the outer fold of the collar partly broken away, to illustrate the manner of 30 connection of the fastener with the collar, and the positioning of the fastener with respect to the fold of the collar; Fig. 2 is a detail view of a portion of a collar, also illustrating the fastener connected in the 35 buttonhole of the collar; Fig. 3 is a detail vertical section illustrating the fastener in active position; Fig. 4 is a detail perspective of the fastener removed from the collar, and clearly illustrating the front of the 40 fastener; and Fig. 5 is another detail perspective view of the fastener removed from the collar, illustrating the rear portion of the fastener.

Referring particularly to the drawing 45 wherein the fastener is shown adapted for use with collars, the same is constructed of a single length of wire centrally bent to form a V-shaped attaching portion 5, provided with oppositely disposed yieldable 50 limbs 6 which diverge upwardly from the apex 7 of said fastener. This attaching portion is adapted to be inserted in the rear buttonhole of the usual innerfold A of the collar B and positioned between the folds 55 of the collar when in active position, as better shown in Fig. 3 of the drawing, and

owing to the particular configuration of this attaching portion greatly facilitates the application of the same to the collar. The upper terminals 8 of each of the limbs 6 is 60 bent inwardly and upwardly inclined as at 9, to a distance substantially alining vertically with the inner portion of the apex or bite portion 7, of the V-shaped attaching portion 5. The wire is thence curved 65 laterally and forwardly as at 10, thence downwardly and outwardly in spaced parallel relation with the upwardly inclined portion 9, as at 11, to present a pair of obliquely disposed diverging inverted U-shaped interlocking sections 12. It will therefore be 70 seen when the V-shaped attaching member 5 is applied in the manner heretofore described, it causes the interlocking sections 12 to be sprung inwardly, until the latter are 75 alined with the rear buttonhole of the collar, whence they are sprung outwardly by the resiliency of the legs 6, and arrested in binding engagement with the side walls 13 of the buttonhole of the collar B. The outermost limb 11 of the U-shaped interlocking sections 12, are inclined downwardly in 80 spaced parallel relation with the limbs 5, for a portion of their length and at a point below the point of bending of the sections 85 12 therewith, as at 13, thence bent outwardly and upwardly in spaced parallel relation with the portion 13, as at 14, to form a pair of opposed diverging U-shaped self-engaging neck band portions 15. The outermost limb 16 of the U-shaped neck band engaging portions is flattened as at 17 to facilitate 90 the engagement of the portions 15 under the neck band C, and render the same what might be termed as self-engaging portions, 95 that is to say, after the fastener is attached to the collar and when it is desired to attach the collar to the shirt D, these portions will gradually ride up under the neck band, 100 without the necessity of using either hand, and thereby when the collar is placed around the neck band C of the shirt, the fastening of the collar at the front can be immediately and readily accomplished. The U-shaped neck band engaging portions 15, 105 are not only arranged in diverging relation and parallel with the limbs 6, but are further disposed at right angles with respect to the inverted U-shaped interlocking connectors 12, and adapted to frictionally engage 110 with the neck band C of the shirt D, whereby it will not only prevent the riding

up of the collar on the shirt, but will further prevent any slight rotation of the collar with respect to the neck of the wearer, should the front buttonholes of the collar become slightly worn or marred, and thereby presenting the collar on the wearer at all times with a very neat and attractive appearance.

From the foregoing description, taken in connection with the accompanying drawing, the advantages of construction and of the method of operation will be readily apparent to those skilled in the art to which the invention relates. While I have described the principles of operation of the device together with the device which I now consider to be the best embodiment thereof, I desire to have it understood that the device shown is merely illustrative and that such advantages may be made when desired as are within the scope of the claim appended thereto.

Having thus described the invention, what I claim is:

25 A clamp as a substitute for a collar button for securing the back of a collar to the back of a shirt band, formed from a piece

of resilient wire which is bent to provide a V-shaped head that is adapted to be inserted through the button hole of the collar and to lie against the back of the collar, the angular limbs of the head being yieldable and having their upper terminals extended inwardly and upwardly and from thence continued downwardly in a line with the said inward and upward extensions to provide U-shaped gripping members which contact with the end wall of the button hole and with the opposite sides of the collar, the ends of the said U-shaped members being bent downwardly in a line one with each of the limbs of the head and from thence bent outwardly and upwardly to provide shirt neck band engaging members, and said members being reduced and flattened from their free ends to facilitate the engagement thereof with the neck band of the shirt.

In testimony whereof I affix my signature in presence of two witnesses.

WILLIAM S. WICKHAM.
